UNITED STATES PATENT OFFICE.

BERNHARD BRAUN, OF BROOKLYN, NEW YORK.

SAFETY-TREAD HORSESHOE.

SPECIFICATION forming part of Letters Patent No. 783,567, dated February 28, 1905.

Application filed April 11, 1903. Serial No. 152,212.

To all whom it may concern.

Be it known that I, BERNHARD BRAUN, a subject of the Emperor of Germany, residing in Brooklyn, in the county of Kings and State 5 of New York, have invented certain new and useful Improvements in Safety-Tread Horseshoes, of which the following is a full, clear, and exact specification.

My invention relates to a safety-tread horse- 10 shoe; and its object has been to provide one which shall have the desirable qualities of durability, cheapness, and efficiency; and it consists of the combinations and parts hereinafter more particularly described.

15 In the drawings representing one form of my invention, Figure 1 is a plan view of my invention. Fig. 2 is a sectional view of Fig. 1 on line *y* *y*, and Fig. 3 is a detail view of the detachable spurs for use in slippery 20 weather.

In the drawings, 1 represents the shoe proper of conventional shape, which may be made of iron, steel, or any other suitable material. The upper side of the shoe is provided with the 25 usual projecting lugs 2 and 3 for the purpose of adjustment to the foot of the animal. A strengthening-bar 12 is formed adjacent to the heels of the shoe and serves to strengthen the shoe, as well as to assist in retaining the pad 30 10, presently to be described. Upon the lower or tread surface of the shoe and along the periphery thereof is a channel or recess 4, adapted to receive some safety-tread material, such as the hempen rope 5. (Shown in the drawings.) A second or auxiliary channel is dis-

35 posed adjacent to the inner part of the channel already described and concentric thereto. Suitable nail-holes 6 extend through the shoe into the outer channel only, and the shoe is 40 provided at the ends or heels with suitable recesses 7, preferably screw-threaded to receive the detachable spurs 8, which will be found useful on icy pavements to prevent slipping. The nail-holes are so arranged that 45 when the nails are inserted the heads are entirely within the channel containing the soft-tread material and are thus removed from the tread-surface of the shoe. By using the same channel for both the soft-tread material and 50 the nails the whole available surface of the

shoe may be utilized and a maximum efficiency obtained.

The safety-tread material may be held in place by any suitable means—such, for instance, as the spurs or projections 9, which engage between the strands of the coil of hemp. In winter snow, ice, &c., are very apt to become packed between the sides of a horse's shoe and interferes with the safety qualities of any shoe. To prevent this, I provide a rubber or cork packing 10, which fits within the arms of the shoe at the heels and is held in place by suitable spikes 11. The cork protecting-pad 10 is placed below the cross-bar 12, which serves as a strengthening 65 device. The spurs 8 may be attached to the shoe by any suitable means—as, for instance, by screwing them in, as indicated in the drawings. Where this is done it will be convenient to provide the heads thereof with a 70 flat portion 13, which may be readily engaged by a wrench or other implement and readily screwed home.

The location of the pad 10 in Figs. 1 and 2 close to the heels of the shoe and the detachable spurs or calks is important, for the reason that the snow, ice, sand, or other material plowed up and thrown forward by the calks is prevented from entering between the sides of the shoe, while the space in front of the 80 pad and cross-bar is left open, so that the hoof need not be too closely confined either for comfort of the animal or for convenient examination of the hoof.

It is obvious that many modifications and 85 changes may be made in my invention without departing from the spirit thereof, and I do not limit myself to the particular structure shown; but

What I claim, and desire to secure by Letters Patent, is—

1. In a safety-tread horseshoe having suitable channels therein, a safety-tread material partly within one of said channels and held in place by suitable spurs or projections, nail-holes extending through said shoe into one of said channels, a strengthening-bar adjacent to the heels of said shoe, detachable calks on said heels, a free space in front of said bar, a safety pad or cushion adjacent to the heels of 95 100

the shoe and means for holding said cushion, substantially as described.

2. In a safety-tread horseshoe having suitable channels therein, a safety-tread material partly within one of said channels and held in place by suitable spurs or projections, nail-holes extending through said shoe into one of said channels, a cross-bar located at the rear part of the shoe, a free space at the forward 10 part of the shoe, detachable calks on the heels of said shoe, a safety pad or cushion at the rear of the shoe and means for holding the said pad, substantially as described.

3. In a safety-tread horseshoe having suitable channels therein, a safety-tread material partly within one of said channels and held in place by suitable spurs or projections, nail-holes extending through said shoe into one of said channels, a cross-bar located at the rear 15 part of the shoe, a free space formed by the front and side portions of the shoe and the cross-bar, calks on the heels of said shoe, a safety-pad adjacent to said calks and means for holding said pad, substantially as described.

4. In a safety-tread horseshoe having suitable channels therein, a safety-tread material partly within one of said channels and held in place by suitable spurs or projections, nail-holes extending through said shoe into one of said channels, a cross-bar at the rear part of 20 said shoe, a free space formed by the front and side portions of said shoe together with the said cross-bar, calks on the heels of said 25 shoe, a pad or cushion at the rear of the bar adjacent to the calks and means for securing said pad or cushion, substantially as described.

5. In a safety-tread horseshoe having suitable channeled portions, a safety-tread material partly within one of said channeled portions, and held in place by suitable means, nail-holes through said shoe extending into one of the channeled portions, a cross-bar connecting the rear portions of said shoe, a free space 40 formed by the front and side portions and the cross-bar, calks on the heels of said shoe, a safety pad or cushion adjacent to said heels and retained in position by the said bar, the rear of said shoe and the inwardly-projecting heels 45 of said shoe together with spurs on said bar and sides of said shoe, substantially as described.

6. In a safety-tread horseshoe having suitable channels therein, a strengthening-bar adjacent to the heels of the shoe, a safety-tread 50 material partly within one of said channels and held in place by suitable spurs or projections, nail-holes extending through said shoe into one of said channels, detachable calks

secured to the heels of said shoe, a safety pad or cushion adjacent to said calks at the heels 60 of the shoe, means consisting of said cross-bar and spurs thereon and on the sides of the shoe for holding said pad, substantially as described.

7. In a safety-tread horseshoe, channels substantially parallel with the periphery of the 65 front portion thereof, a safety-tread material partly within one of said channels and held in place by suitable spurs or projections, nail-holes extending through said shoe into one of said channels, a strengthening cross-bar, near 70 the heels of said shoe, detachable calks on said heels, a safety pad or cushion adjacent to said calks and means consisting of the cross-bar and spurs on the sides of the shoe and on the cross-bar for holding said pad or cushion, substantially as described.

8. In a safety-tread horseshoe having channels therein, a safety-tread material partly within one of said channels and with suitable holding means, nail-holes extending through 80 said shoe into one of said channels, a cross-bar adjacent to the heels of said shoe, a free space between the front and sides of the shoe and the said cross-bar, detachable calks on the 85 heels of said shoe, a safety pad or cushion adjacent to said heels and said calks, and means consisting of the cross-bar and spurs on said bar and the sides of the shoe for holding said pad, substantially as described.

9. A safety-tread horseshoe comprising a 90 frame, nail-holes through said shoe a peripherally-disposed cushion secured in the forward part of said frame, a bar formed integral with said frame connecting the rear portions thereof, an opening through said shoe bounded by 95 the forward portion of the shoe and by said bar, calks at the rear of said frame, a pad or cushion forward of and adjacent to said calks, and means for securing said pad or cushion, substantially as described.

10. A safety-tread horseshoe comprising a 100 U-shaped frame having a strengthening cross-bar, nail-holes through said shoe, a peripherally-disposed cushion in said frame, a free space bounded by the said frame and said bar, 105 calks on the heels of the shoe, a safety pad or cushion at the rear of the shoe forward of said calks and means for securing said pad or cushion, substantially as described.

In testimony whereof I have hereunto affixed my signature in the presence of two witnesses.

BERNHARD BRAUN.
